UNITED STATES PATENT OFFICE.

BENJAMIN F. TOZIER, OF VENICE, CALIFORNIA.

GAME OF SKILL.

Application filed October 3, 1921. Serial No. 504,950.

To all whom it may concern:

Be it known that I, BENJAMIN F. TOZIER, a citizen of the United States, residing at Venice, in the county of Los Angeles and 5 State of California, have invented a new and useful Game of Skill, of which the following is a specification.

This invention relates to amusement devices in which competing objects are caused 10 to travel along courses, the speed of travel thereof being determined by the skill of the operators in manipulating certain mechanisms connected therewith.

It is an object of my invention to provide 15 a game in which the competing objects are guided throughout an irregular course by the respective players participating therein.

It is a further object of this invention to provide 20 a game of this character in which the ordinary speed of travel of the competing objects may be controlled by the players.

It is a still further object of this invention to provide such a game in which the 25 speed of travel of the competing objects will be altered upon their passing outside the boundaries of their respective courses.

It is also an object of this invention to provide such a game in which all the competing 30 objects will be stopped upon the end of the course being reached by any one of the objects.

And it is a further object of my invention to provide in such a game an indicating device 35 which will denote the winner of the competition, thereby eliminating all cause for dispute upon the part of the players participating therein.

Further objects and advantages will be 40 made evident hereinafter.

Referring to the drawings which are for illustrative purposes only,

Figure 1 is an elevational sectional view of a game embodying my invention taken 45 upon a plane represented by the line 1—1 of Fig. 2.

Fig. 2 is a plan view corresponding to Fig. 1, a portion thereof being in section upon a plane represented by the line 2—2 50 of Fig. 1, to disclose part of the operating mechanism.

Fig. 3 is a diagrammatic plan view illustrating a portion of the steering mechanism employed in connection with my device.

Fig. 4 is a fragmentary view illustrating

one of the competing objects standing upon the course provided therefor.

Fig. 5 is a sectional view taken on a plane represented by the line 5—5 of Fig. 4.

Fig. 6 is a section taken on a plane represented by the line 6—6 of Fig. 4.

Fig. 7 is a fragmentary detail taken as indicated by the arrow 7 in Fig. 4.

Fig. 8 is a diagram showing the electrical connections I employ in the device herein described and illustrated.

In this presentation of the embodiment of my invention I show a number of competing objects consisting of miniature automobiles 11 mounted upon a sloping table 12. Upon 70 the table 12 a number of irregular courses 13 are laid out, and channels 14, centrally located with respect to the courses 13, are formed in the table 12. It is the idea in this invention that the players participating 75 therein shall steer the automobiles as near centrally as possible along their respective courses by manipulating the steering wheels 15 which extend from a suitably located table 16.

In Fig. 4 and the accompanying figures provided to further illustrate the construction shown in Fig. 4 I show a form of construction which may be employed in connection with the automobiles 11. Upon the 85 front axle 20 are mounted wheels 21 by means of steering knuckles 22 and vertically projecting through a lug 23 extending from the axle 20 is a shaft 24 adapted to extend below the table 12 and to have mounted upon 90 the lower end thereof a yoke 25. Near the upper end of the shaft 24 is mounted a lever 26 from the end of which extend links 27 having connection with the arms 28 of the steering knuckles 22. Through this arrangement any rotative movement imparted to the shaft 24 will cause a corresponding movement of the lever 26, and through the interconnecting links 27 the wheels 21 are caused to assume an angular position relative to the axle 20 and thus provide a means for steering the automobiles 11 from a point underneath the table 12.

Mounted upon the rear axle 30 is a gear 31 which may be driven through an intermediate gear 32 from a pinion 33 mounted upon the shaft of a motor 34 situated within the housing 35 of the automobile. The rear wheels 36 and 37 are of a suitable electric current conducting material and rest upon 110

2

copper plates 38 and 39 extending along both sides of the grooves 13. These plates 38 and 39 are connected with rheostats 40 operated by the players through the medium of lever 41 mounted upon shafts 42 which extend centrally through the steering wheel posts 43. The electric current for driving the motor 34 is introduced into the plates 38, the strength of same being regulated by the respective players from the rheostats 40, and is taken off from the plates 38 and 39 by the wheels 36 and 37 and is carried therefrom by conductors, not shown, to the motor 34. It will be noted that the wheel 36 is mounted directly upon the shaft 30 while the wheel 37 is insulated therefrom by suitable insulating material 44 and the current is taken from the wheel 37 by means of a brush 45.

20 As shown in Fig. 3 of the drawing the yoke 25 mounted upon the lower end of the shaft 24 has the ends 46 thereof connected to a flexible cord or cable 47. The cable 47 makes several turns around spools 48 and 49 carried upon a centrally pivoted yoke 50. The outwardly disposed portions 51 of the cable 47 pass around sheaves 52 and crossing at a point 53 extend over sheaves 54 and therefrom extend to the spools 48 and 49. 25 When the yoke 50 is swung into a position indicated by the dotted lines 54 those portions of the cable 47 extending from the spool 48 will be progressed as indicated by the arrow 55 while those portions connecting with the spool 49 will be retracted as indicated by the arrow 56, thus causing the yoke 25 to assume the position shown in dotted lines whereupon the shaft 24 will be rotated and the wheels 21 caused to assume 30 an angular position thus providing a means of steering the automobile 11 from a remote position. The disposal of the spools and sheaves and the manner in which the cable is placed thereupon makes it possible to laterally move the yoke 25 and those portions of the cable connected thereto without changing the relative position of the yoke 25 to that of the yoke 50.

35 The yoke 50 is mounted upon a shaft 60 which also mounts a small beveled gear 61 enmeshed with a mitre gear 62 mounted upon a horizontally extending shaft 63. Through sets of mitre gears 64 and an interconnecting shaft 65 the gear 62 may be rotated from a shaft 66 through enmeshing of a mitre gear 67 with the mitre gear 68 mounted upon the steering post 43, thus the 40 operation of the steering wheel 15 will cause the partial rotation of the shaft 50 and the automobile will be steered through the cable mechanism heretofore described and illustrated in detail in Fig. 3. Each of the automobiles 11 is provided with the equipment illustrated in the connection with the first 45 machine and the steering connection from

their respective steering wheels 15 is accomplished through the gearing arrangements 70.

It requires considerable skill to direct an automobile along such an irregular course as I have shown at 13 and I have provided a means for considerably reducing the speed of travel of the automobiles 11 when they fail to adhere to the center of their respective courses. In front of each axle 20 I place a leg 75 which extends downwardly through the channel 13 as illustrated in Figs. 4 and 7. Upon the front face of the leg 75 I pivot upon a screw 76 a lever 77 having a cross arm 78 integrally formed upon the lower end thereof. The upper end 79 of the lever 77 operates between a pair of flexible blades 80 and 82 upon which are mounted contact points 81. The ends of the cross arm 78 extend somewhat beyond the confines of the leg 75 so that if the automobile is steered to one side of the course, the end of the cross arm will come in contact with one of the sides 83 of the channel 14 and the lever 77 will be thrown into an angular position which will force one of the plates 80 or 82 outwardly, thus breaking the contact 81 and causing the electric current otherwise passing therethrough to be diverted through a suitable resistance before reaching the motor 34 and causing a drop in the voltage which will result in retarding the speed of the motor.

At the ends 85 of each of the courses 13 I provide buttons 86 adapted to close contact switches 87 upon the automobiles 11 reaching the ends of their respective courses and coming in contact with the buttons. The closing of any of the contact switches will cause the actuation of a circuit breaker in the feed circuit from which the leads to the respective rheostats 40 are taken, thus stopping all of the automobiles 11 and also closing a circuit with one of the respective solenoids 88 or other suitable magnetic means, which causes a target 89 to be lifted and thus expose to view some means or word indicating the winner. It is especially desirable that a means of designating the winner be provided as in the present competitive games a great deal of argument arises when several of the objects reach the ends of their courses at apparently the same time, while with the use of my device all of the objects will be stopped immediately upon one 120 of the competing objects completing the course.

In Fig. 8 I illustrate in diagrammatic form the electrical connections employed in the operation of this device. Current is supplied to main conductors 90 and 91 from a source 92 and the leads 93 and 94 are taken therefrom. Lead 93 is direct connected to the plate 38 from which current is conducted through the wheel 36 and the con-

ductor 38' to the motor 34. Leads 94 connect with the rheostat 40 and from thence connection is made with the plates 39 through conductors 95. Conductors 96 lead 5 to the plates 80 which have contact at 81 with the plates 82 which are connected to the motors 34 by conductors 97. The amount of current delivered to the motor is regulated by rheostat 40 and the motor 34 10 is energized causing the automobiles to advance along their courses. When the contacts 81 are broken due to the automobiles running into the side of the course, the current must pass through resistances 98 which 15 causes a drop in the voltage and a consequent reduction in the speed of the motor which delays the automobile in its progress toward the end of the course. When one of the automobiles reaches the end of its 20 course, one of the buttons 86 is thrown forward and actuates a switch 87 which closes circuits 99 and 100 taken off from the conductors 105 and 106 leading from a battery 107, the respective solenoid 88 is energized 25 causing the winning automobile to be indicated and causing the actuation of an independently tripped circuit breaker 110 located in the conductor 91, thus cutting off current to all of the motors 34 and stopping 30 the automobiles at whatever position they may happen to be in at that time.

I claim as my invention:

1. In a game, the combination of: a number of competing objects; courses along which said objects may be propelled; means for propelling said objects along said courses; steering means whereby said objects may be directed along said courses by the players participating in said game; 35 means operable by said players to control the speed of said objects along said courses; and means adapted to reduce the speed of travel of said objects upon their passing outside the boundaries of their respective courses.
2. In a game, the combination of: a number of competing objects; courses along which said objects may be propelled; means for propelling said objects along said courses; steering means whereby said objects may be directed along said courses by the players participating in said game; means operable by said players to control the speed of said objects along said courses; 45 means adapted to reduce the speed of travel of said objects upon their passing outside the boundaries of their respective courses; and means consequent upon the reaching of the end of the course by any one of said objects to cause the stopping of all of said objects in their respective positions.
3. In a game, the combination of: a number of competing objects; courses along which said objects may be propelled; means 50 for propelling said objects along said courses; steering means whereby said objects may be directed along said courses by the players participating in said game; means operable by said players to control the speed of said objects along said courses; 55 means adapted to reduce the speed of travel of said objects upon their passing outside the boundaries of their respective courses; and means consequent upon the reaching of the end of the course by any one of said objects to cause the stopping of all of said objects in their respective positions.
4. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; and means consequent upon the reaching of the end of the course by any one of said objects to cause the stopping of all of said objects in their respective positions, 60 and the display of a signal indicating the winning object.
5. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; and means consequent upon the passing of said vehicles without the bounds of said courses to divert said current through a resistance and thus reduce the speed of the motor.
6. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; and means consequent upon the passing of said vehicles without the bounds of said courses to divert said current through a resistance and thus reduce the speed of the motor; mechanism at the end of each of said courses to actuate a circuit breaker upon the reaching of the end of one of said courses by one of said vehicles whereby the supply of current to all of said motors will be discontinued.
7. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; and means consequent upon the passing of said vehicles without the bounds of said courses to divert said current through a resistance and thus reduce the speed of the motor; mechanism at the end of each of said courses to actuate a circuit breaker upon the reaching of the end of one of said courses by one of said vehicles whereby the supply of current to all of said motors will be discontinued; and mechanism at the end of each 130

of said courses for indicating the arrival of one of said vehicles at the end of said course respective thereto.

7. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; means consequent upon the passing of said vehicles without the bounds of said courses to divert said current through a resistance and thus reduce the speed of the motor; mechanism at the end of each of said courses to actuate a circuit breaker upon the reaching of the end of one of said courses by one of said vehicles whereby the supply of current to all of said motors will be discontinued; and magnetically actuated mechanism at the end of each of said courses for indicating the arrival of one of said vehicles at the end of said course respective thereto.

8. In a game, the combination of: a number of competing vehicles; courses along which said vehicles may be propelled; motors mounted by said vehicles to propel same; means for supplying current to said motors; means for varying the strength of said current; steering means whereby said vehicles may be directed along said courses by the players participating in said game; and means consequent upon the passing of said vehicles without the bounds of said courses to reduce said current and thus reduce the speed of the motor.

9. In a game, the combination of: a number of competing objects; courses along which said objects may be propelled; means for propelling said objects along said courses; steering means whereby said objects may be directed along said courses by the players participating in said game; means operable by said players to control the speed of said objects along said courses; means adapted to reduce the speed of travel of said objects upon their passing outside the boundaries of their respective courses; and means consequent upon the reaching of the end of the course by any one of said objects to cause the displayal of a signal indicating the winning object.

10. In a game, the combination of: a number of competing objects; courses along which said objects may be propelled; means for propelling said objects along said courses; steering means whereby said objects may be directed along said courses by the players participating in said game; means operable by said players to control the speed of said objects along said courses; means adapted to reduce the speed of travel of said objects upon their passing outside the boundaries of their respective courses; and means consequent upon the reaching of the end of the course by any one of said objects to cause the displayal of a signal indicating the winning object and to prevent the indication of the subsequent arrival of any of the remaining competing objects.

In testimony whereof, I have hereunto set my hand at Los Angeles, California, this 26th day of Sept., 1921.

BENJAMIN F. TOZIER.
